UNITED STATES PATENT OFFICE.

LOBEGOTT MOLLART, OF WATERTOWN, WISCONSIN, ASSIGNOR TO G. B. LEWIS COMPANY, OF WATERTOWN, WISCONSIN.

BOX-FASTENER.

1,102,286.

Specification of Letters Patent.

Patented July 7, 1914.

Application filed February 9, 1914. Serial No. 817,566.

To all whom it may concern:

Be it known that I, LOBEGOTT MOLLART, a citizen of the United States, and resident of Watertown, in the county of Jefferson and 5 State of Wisconsin, have invented certain new and useful Improvements in Box-Fasteners; and I do hereby declare that the following is a full, clear, and exact description thereof.

10 My invention consists in what is herein particularly set forth with reference to the accompanying drawings and pointed out in the claims of this specification, its object being to provide simple, economical, efficient 15 and durable box-fasteners especially designed for returnable shipping-boxes having hinged covers.

Figure 1 of the drawings represents a front elevation of one of my improved box- 20 fasteners partly broken away, together with a fragment of a sealing-strip applied thereto, and Fig. 2, a sectional view indicated by line 2—2 in Fig. 1.

Referring by numerals to the drawings, 3 25 indicates a plate attachable to the top of the lid of a box to project somewhat from the adjacent edge of the same. The projecting portion of the plate is preferably bent downward more or less from a horizontal 30 plane and, whether bent or otherwise, it is provided with a slot 4 in a direction longitudinally of the lid to which it is fastened by rivets or other suitable devices for which 35 apertures are provided in said plate, one of these apertures being shown at 5 in Fig. 2.

Bent upon itself in engagement with the slot 4 of the plate 3 is one end of a hasp 6 having the longitudinal edges thereof angularly notched adjacent to its other end. 40 The notches 7 of the hasp are for the engagement of upper outer and preferably upwardly inclined flanges 8 of another plate 9 that is fastened to the outside of the front wall of the box to which it is fastened by 45 rivets or other suitable devices, said plate 9 being provided with apertures 10 for the engagement of said fastening devices. A depending center lug 11 of the plate 9 is provided with a horizontal slot 12, and a 50 portion of said lug is outwardly bent to form a vertically disposed stop-flange 13 at an approximate right-angle to the remainder thereof.

In pivotal connection with the plate 9 is 55 a gravity latch 14 the same being a strip of

reduced thickness in one direction from its pivot. The other, thick end of the latch has a slot 15 therein registerable with the slot 12 in the plate-lug 11 when said latch is in its normal vertical position abutting the 60 stop-flange 13 of said lug. The light end of the latch 14 opposes the hasp 6 caught in engagement with the flanges 8 of the plate 9, to fasten the box-lid in closed position and said latch is fastened in this position by 65 a metallic-seal wire or strip 16 engaging the registering slots 12 and 15 aforesaid.

To release the hasp 6, the latch 14 is swung on its pivot to have its light end clear said hasp, the movement of its heavy 70 end being away from the stop-flange 13 of the plate-lug 11. After a disengagement of the hasp 6 from the catch-plate 9, the latch is permitted to return to normal position where it remains back of said hasp that is 75 from time to time reengaged with said catch-plate while the box is in use. To again fasten the box lid in closed position, the latch 14 is swung out of its normal position to permit of the hasp 6 falling full back 80 in the notch between the flanges 8 of the catch-plate 9, and said latch being freed it returns to normal position forward of said hasp to hold the same in its engagement with said catch-plate. 85

I claim:

1. A fastener comprising a plate-member attachable to the lid of a box to project at one end therefrom, another plate-member attachable to the front of the box-body 90 and having a recessed upper outer flange, a hasp-member having its upper end in swinging connection with the outer end of the box-lid plate-member and which is engageable with the recess of the flange of the box- 95 body plate-member to extend under said flange, and a hasp-facing gravity latch-member in pivotal connection with said box-body plate member.

2. A fastener comprising a plate-member attachable to the lid of a box to project at one end therefrom, a hasp-member hung in connection with the outer end of said plate-member and having the longitudinal edges thereof angularly notched adjacent to its lower end, another plate-member attachable to the front of the box-body and having an upper outer flange provided with a recess with which the narrow portion of the hasp-member between its notches is engageable, 105 110

2
and a hasp-facing gravity latch-member in pivotal connection with the box-body plate-member.

3. A fastener comprising a plate-member attachable to the lid of a box to project at one end therefrom, another plate-member attachable to the front of the box-body and having a recessed upper outer flange and a depending lug provided with an outer stop-flange; a hasp-member having its upper end in swinging connection with the outer end of the box-lid plate-member and which is engageable with the recess of the flange of the box-body plate-member to extend under said flange, and a hasp-facing gravity latch-member in pivotal connection with said box-body plate member, said stop-flange serving to limit swing of the latch-member in one direction.
- 15 4. A fastener comprising a plate-member attachable to the lid of a box to project at one end therefrom, another plate-member at-

tachable to the front of the box-body and having a recessed upper outer flange and a depending apertured lug, a hasp-member having its upper end in swinging connection with the outer end of the box-lid plate-member and which is engageable with the recess of the flange of the box-body plate-member to extend under said flange, and a hasp-facing gravity latch-member in pivotal connection with said box-body plate member, the latch-member being provided with an aperture registrable with the one in the lug of said box-body plate.
